Patented Oct. 3, 1922.

FIG. 1.

FIG. 2.

FIG. 3.

Inventor
Frank Dutcher,

By A. S. Patterson,

Attorney

UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

TIME BURNING RAILWAY SIGNAL FUSEE.

Application filed April 25, 1921. Serial No. 464,109.

To all whom it may concern:

Be it known that I, FRANK DUTCHER, a citizen of the United States, residing at Versailles, in the county of Allegheny and 5 State of Pennsylvania, have invented certain new and useful Improvements in Time Burning Railway Signal Fusees, of which the following is a specification, reference being had therein to the accompanying drawings.

This invention relates to improvements in time burning railway signal fusees, and pertains to certain improvements in means for insuring the lighting of the fusee compound 15 by the primer or lighting head and of holding the primer in position during the burning thereof.

In the accompanying drawings:

Figure 1 is a perspective view of a railway signal time burning fusee, which embodies my invention.

Fig. 2 is an enlarged sectional view of the lighting end of the fusee.

Fig. 3 is a detached enlarged perspective view of my improved means for insuring the lighting of the fusee compound from the lighting head and of holding the lighting head in position.

It is well known to those skilled in this art that railway signal time burning fusees comprise a paper case 1, in which the fusee time burning compound 2 is placed, and that in the upper end of the case and extending down into the fusee compound 2 is what is termed in the art as a lighting head or priming compound 3. It is also well known to those skilled in the art that fusees are lighted on the safety match principle, that is to say, there is a projecting chlorate of 30 potassium lighting compound 4, at the lighting end of the fusee, which is in contact with the lighting head 3, and that the fusee is provided with a removable cap (not shown) which contains a lighting material 35 which is complementary to the chlorate 4, whereby the chlorate of potassium compound 4 is ignited by friction with the complementary lighting material on the cap.

The fusee compound 2 is slow burning 50 for the purpose of burning a specified length of time and is preferably the perchlorate compound of the Niditch Patent No.

954,330, dated April 5th, 1910, and the lighting head 3 is a relatively fast burning compound, consisting of chlorate of potassium, 55 carbonate of strontium; charcoal; burnt umber and shellac. The shellac is dissolved in alcohol making it a semi-liquid, which is then added to the above powdered composition, which makes it a thin plastic 60 mixture. This plastic mixture forming the lighting head 3 is placed in an opening 5, formed in the fusee compound 2, and afterwards the chlorate of potassium compound 4 is placed thereon when in a plastic state. 65

The lighting head 3, as stated, is a fast burning compound and ignites at a relatively low temperature, so that it is readily lighted by the lighting compound 4, and owing to its fast burning character, the 70 burning particles thereof are thrown with quite a good deal of force from the open end of the fusee, and it has been found desirable in the art to provide means for fastening the lighting head to the fusee compound 2, and various means have been provided for this purpose.

Although the lighting head 3 is a fast burning compound, it has been found in practice to sometimes fail to light the fusee 80 compound 2. Since these time burning fusees are used for safety signals on railroads, a single failure of the fusee to burn is liable to cause a serious accident. Therefore any means that will either insure the 85 lighting of the fusee compound, or to make its lighting more certain is of prime importance in railway signal fusee constructions.

It is the object of my present improvement to provide a combined fire conveying 90 and holding member which passes through the lighting head into the fusee compound and is of such a character as to make more certain or to insure the lighting of the fusee 95 compound by the burning of the lighting head.

I have discovered that the dissolved shellac, in the lighting head compound 3, is absorbed by the relatively dry fusee compound surrounding it, in sufficient quantity so that when it dries a hard shellac saturated wall 6 surrounds the lighting head 3, and that this vary hard shellac saturated wall 100

interferes with the conveying of the fire from the lighting head to the fusee compound 2, and is largely, if not wholly, responsible for the failure of the lighting head to ignite the fusee compound 2.

For the purpose of assisting the lighting head 3 in conveying its fire to the fusee compound 2, a wood peg has been passed through the lighting head into the fusee compound, 10 and the wood peg is saturated with a combustible compound. This form of device is shown in the Niditch Patent No. 1,015,062, January 16th 1912 and No. 1,068,267, July 22nd 1913. The patentee Niditch appears 15 not to have discovered that the failure of the lighting head to light the fusee compound was due to the forming of a very hard shellac saturated wall surrounding the lighting head, nor indeed to have discovered 20 that there was any such hard surrounding wall. The burning products of the wood peg are carried out through the open end of the fusee by the force of the rapid burning of the lighting head, and, therefore, the 25 light burning products of the wood peg do not remain within the fusee to convey their fire to the fusee compound proper, and the wood peg forms only one depending element for conveying the fire to the fusee compound. Furthermore, the peg passes through 30 the center and lower end of the lighting head, and is, therefore, removed from the hard shellac saturated wall which surrounds the lighting head.

35 I have discovered a form of fire conveying and lighting head holding member which is not blown out of the fusee by the blow-flame effect of the rapidly burning lighting head compound 3, but which will remain in the 40 fusee in its fused or approximately fused condition for conveying its fire to the fusee compound 2.

This new member consists of an annealed wire which is preferably in the form of an 45 elongated U, or hairpin shape, as indicated at 7. This wire 7 is composed of an annealed soft metal, and preferably of a character which is fused by the heat from the lighting head 3. Fig. 2 shows twice the usual cross- 50 sectional size of the full size fusee, and the member 7 in Figs. 2 and 3 is shown twice the full size. The diameter of the wire, of which the member 7 is formed, may vary and also the length of the member may vary. 55 As shown, the leg portions of the member 7 pass through the lighting head 3, near its outer wall, which in full size is one-half the thickness shown in Fig. 2, thus bringing the depending legs of the member 7 very close 60 to the surrounding hard shellac saturated wall 6, and that the two legs pass through the lower portion of the lighting head and through the surrounding wall 6 and into the fusee composition 2, at two separate points.

65 When the upper end of the lighting head

is lighted by the lighting compound 4, the hot blow-like flame quickly fuses or approximately fuses the upper double end 8 of the member 7, and this hot heavy metal is not blown from the fusee and remains therein. 70 As the lighting head 3 continues to burn, the parallel leg portions of the member 7, become fused or approximately fused and serve to materially add to the conveying of the fire from the lighting head 3, through the shellac saturated wall 6 to the fusee compound. 75

I have found in actual practice, that my improved holding and fire conveying member is an important improvement over those heretofore used and, in practice, insures the conveying of a lighting fire from the lighting head to the fusee compound 2, and also prevents the lighting head from being blown out of the fusee compound, owing to its rapid burning, and also prevents the lighting head from being thrown or knocked out of the fusee, when it is thrown from a rapidly moving train after it is lighted. 85

By reason of the outwardly bent lower 90 ends 9, the legs of the U-shaped member 7 are caused to spread outward, as shown in Fig. 2, as the member is being forced into position into the fusee compound 2.

My improved member 7 is forced through 95 the lighting head 3, before it has dried out and its lower ends are hammered or forced into the fusee compound 2, by hammering or pushing upon its upper doubled end 8.

The best results are obtained by having 100 the U-shaped member 7 formed of a metal which is fusible by the temperature of the burning lighting head, though I desire it to be understood that greatly improved results can be obtained even if the metal is not 105 completely fusible, but it is approximately fusible.

By having the metal of the U-shaped member 7 wholly fusible, it falls within the fusee 110 as the lighting head and the fusee compound burn down and prevents any outwardly extending structure, and this will be equally true if the metal is approximately fusible for then it will also fall into the fusee, as the compounds are burned away from it. 115

I am aware that a cup-shaped woven wire enclosure has been provided for the upper end of the fusee compound with its side walls extending down against the wall of the paper tube, as shown in Patent No. 1,205,928, November 21st, 1916, to E. C. Pfeil and H. O. Bemisderfer, but in this patent the cup-shaped member does not extend through the lighting head and into the fusee composition, and does not serve the function of my combined holding and lighting member 7. To the contrary, the only function of the cup-shaped member 6 of the said patent is to hold the lighting end of the fusee against being blown or knocked out of 120 125 130

the fusee case, and it does not embody the function or principle of my present improvement.

In the commercial fusee, the fusee compound 2 requires quite a high temperature for ignition and, hence, the necessity of the lighting head or primer 3, which latter is ignitable at a much lower temperature than the fusee compound.

10 As to my improved fire conveying holding member, I find that the ordinary soft annealed wire carries out successfully my improvement, and is fusible by the temperature of the burning lighting head, so that 15 there is a molten metal which is too heavy to be blown away by the rapidly burning lighting compound and insures the lighting of the fusee compound.

The soft wire which I have used, may be 20 stated to be composed of carbon, manganese, sulphur, phosphorus and silicon, although the components may be varied so long as a soft wire is used, without departing from the spirit of my invention.

25 Having thus described my invention, what I claim and desire to secure by Letters Patent is:

1. In a railway signal time burning fusee, an enclosing case, a slow burning fusee compound therein, a lighting head at one end of the case and extending into the fusee compound, and a combined fire conveying and holding member consisting of a soft metallic wire passing through the lighting 35 head and into the fusee compound.

2. In a railway signal time burning fusee, the combination of an enclosing case, a fusee compound therein, a lighting head at one end of the case and extending into the fusee 40 compound, and a combined fire conveying and holding member consisting of a fusible

metallic wire passing through the lighting head and into the fusee compound.

3. In a railway signal time burning fusee, the combination of an enclosing case, a 45 fusee compound therein, a lighting head at one end of the case and extending into the fusee compound, and a combined fire conveying and holding member consisting of an elongated U-shaped metallic member with 50 its leg portions passing through the lighting head and into the fusee compound and its bent or doubled end at the outer end of the lighting head.

4. In a railway signal time burning fusee, 55 the combination of an enclosing case, a fusee compound therein, a lighting head at one end of the case and extending into the fusee compound, and a combined fire conveying and holding member consisting of a soft 60 metallic elongated U-shaped wire with its leg portions extending through the lighting head and into the fusee compound and its bent or doubled end at the outer end of the lighting head. 65

5. In a railway signal time burning fusee, the combination of an enclosing case, a slow burning fusee compound within the case, a lighting head at one end of the case and extending into the fusee compound, and a 70 combined fire conveying and holding member consisting of an elongated U-shaped metallic member, composed of metal which is fused by the temperature of the lighting head, the legs of the U-shaped member passing through the lighting head and its bent portion at the outer end of the lighting head. 75

In testimony whereof I hereunto affix my signature.

FRANK DUTCHER.
